UNITED STATES PATENT OFFICE.

DEXTER W. PARKER AND LEWIS F. GRISWOLD, OF MERIDEN, CONNECTICUT, ASSIGNORS TO THE CHARLES PARKER COMPANY, OF SAME PLACE.

EXTENSION-LAMP.

SPECIFICATION forming part of Letters Patent No. 311,520, dated February 3, 1885.

Application filed April 14, 1884. (No model.)

To all whom it may concern:

Be it known that we, DEXTER W. PARKER and LEWIS F. GRISWOLD, both citizens of the United States, residing at Meriden, in the county of New Haven and State of Connecticut, have invented certain new and useful Improvements in Extension-Lamps, of which the following is a specification, reference being had therein to the accompanying drawings.

10 This invention relates to extension-lamps of the sort employing counterbalance-weights; and it consists in making the weight of a cast-metal annular inner part and an encircling sheet-metal part or jacket, the latter being 15 provided with pendants.

Previous to our invention it has been customary to use an open cast-metal ring-shaped weight as a counterpoise to the lamp and its harp or support; but this weight has been 20 used in low-priced lamps, which were composed of material that did not tarnish or corrode. It has advantages over ball-shaped weights, also heretofore used, in admitting the chimney up through the weight, thereby allowing the greatest amount of extension possible to the fixture, and preventing the tarnishing and corroding of the weight. The most serious objection to the ring-shaped weight is that its open shape necessarily makes 25 it cumbersome. This we avoid by suspending ornamental pendants from the lower edge of the weight, which impart to the weight a more finished and artistic appearance, and also serve as a part of the counterpoise, thereby 30 reducing the size of the ring-shaped cast-metal weight.

The main end and object of the invention consists in the employment of an ornamental metallic shell or ring, adapted to be applied to 40 said weight by any suitable method, for the purpose of serving as a cover to the open-shaped cast-metal weight, from which said pendants may be suspended. By the use of the sheet-metal annular shell or ring as a cover 45 to the heavy open cast-metal weight we are enabled, by subjecting the shell to the impression of dies or rolls, to furnish a highly-ornamental open ring-shaped weight, thus admitting of the use of this particular weight 50 in expensive fixtures at small initial cost, the shell of which will not become tarnished by

the action of the smoke and heat from the chimney, because it passes up through the weight.

In the accompanying drawings, Figure 1 55 represents an elevation of an extension-lamp embodying our invention. Fig. 2 represents a vertical section through our improved weight. Fig. 3 represents a detail view of the cast-metal inner ring of said weight. Fig. 60 4 represents a detail view of the sheet-metal jacket.

In said drawings, A designates the canopy of a suspension-lamp fixture; B, the suspending-chains thereof; C, the crown-ring; D, the 65 shade attached to said crown-ring by screws d; E, the base-ring of the shade; F, the harp suspended from said crown-ring; F', arms attached to said harp and supporting said base-ring, and G the lamp, with its chimney G', 70 supported on said harp. The base-ring is provided with pendants e, the base-ring and the crown-ring, as well as the canopy, being made of bronzed sheet metal, so as to present a light and ornamental appearance. 75

In the foregoing parts there is no novelty, and we make no claim thereon.

One end of each suspension-chain B is attached to said crown-ring, and the other end, after being passed over a pulley in the canopy, 80 is attached to the counterbalance-weight H. Heretofore these weights have been made either annular or globular in shape, the former being cast as rings and used on cheap fixtures. They have an advantage over the globular or ball-shaped weights suspended over 85 the chimney, in allowing the smoke and heat to ascend without tarnishing or corroding the weight, and also in allowing the extension of the fixture to the utmost degree possible, inasmuch as the open shape of the weight will 90 permit the chimney to pass up into it.

Our improved annular counterbalance-weight consists of an inner cast-metal ring, H', to which the suspension-chains B are attached, 95 and an outer sheet-metal jacket, H², which encircles said ring H', and is provided with an annular flange, h², extending under the same. This jacket or shell H² is provided with movable glass pendants H³. The upper edge of 100 said jacket or shell is cut to form a series of tongues, h³, and the ring H' is cast with re-

cesses h' in its upper and outer edge. By bending one of said tongues into each of said recesses the parts H' and H^2 are securely fastened together. Of course other means of fastening might be used.

In the complete lamp the weight has the same bronzed or rich gold appearance as the rest of the fixture, and the pendants harmonize with those on the base-ring.

5 The detachable pendants not only add to the beauty of the fixture, but enable us to vary the gravity of the counterbalance-weight at will.

We are aware that it is not new to construct 15 a weight for an extension-lamp in annular shape, the inner part being a casting and the outer part an ornamental shell not of sheet metal. This, however, is not our invention, and we do not claim it, the lightness and 20 beauty of our sheet-metal shell not being found in any other, and additional fastening devices being required by reason of the inflexibility of any shell except a sheet-metal one. We are also aware that ball-shaped 25 weights have been covered with sheet-metal shells of corresponding form. These shells, however, are much more difficult and expensive of construction than our annular shells, and they are also exposed to the tarnishing 30 action of the smoke and flame, which our annular weight avoids, the products of combustion passing up through the open space in the middle when the lamp smokes without touching the shell. Our annular core and annular 35 sheet-metal shell make up a different weight from either of those described, and one which possesses advantages not shared by them.

We are also aware that it is not new to make a weight for extension-lamps of an annularly-grooved cast-metal core and a conical sheet-metal shell, the latter being spun into the grooves of the former to attach them together. 40

Having thus described our invention, what we claim as new, and desire to secure by Letters Patent, is—

45 1. A weight for an extension-lamp, consisting of an annular casting and an inclosing-shell of sheet metal attached thereto and covering the same, for the purpose set forth.

2. A weight for an extension-lamp, consisting of an annular cast-metal core having recesses formed therein, and an annular sheet-metal inclosing-shell provided with tongues, which are bent into said recesses to attach said shell to said core, substantially as set forth. 50

3. In a weight for extension-lamps, the cast-metal inner ring, H' , provided with recesses h' in its upper and outer edge, in combination with the shell H^2 , provided with the annular flange h^2 , which extends under said cast-metal inner ring, and with the tongues h^3 at its upper edge, which are bent into said recesses h' , for the purpose of holding the shell in place, substantially as set forth. 55

In testimony whereof we affix our signatures in presence of two witnesses. 60
